EVIE WALTON BRYSON, OF NEW YORK, N. Y.

TREE DEVICE FOR TRAVELING-BAGS.

1,085,846.

Specification of Letters Patent.

Patented Feb. 3, 1914.

Application filed October 4, 1912. Serial No. 723,879.

To all whom it may concern:

Be it known that I, EVIE WALTON BRYSON, a citizen of the United States, and resident of New York, in the county and State of New York, have invented certain new and useful Improvements in Tree Devices for Traveling-Bags, of which the following is a specification.

This invention relates to a tree device for holding traveling bags or the like in shape and for preserving the same in expanded contour and against deterioration from sagging or breaking down.

The device is adapted for use in traveling bags or the like which are constructed of leather or pliable material. Such bags, being soft and pliable, are liable to sag or break down when out of use, which causes deterioration of the leather or other pliable material of which the bag is constructed.

The object of my invention is to provide a simple and effective means or tree device which may be conveniently and readily employed and inserted in the bag to sustain the same in expanded or normal position when empty and out of use, whereby the contour of the bag will be preserved and deterioration of the leather or pliable material prevented.

A further object of my invention is to provide a device of the class above set forth which is also adapted to be employed in the bag when the latter is packed or in use, and which will under such conditions also effectively serve to hold the bag in open position when desired or to retain the contents of the bag in compact position.

A further object of my invention is to provide a device of the character above set forth which will be adjustable for effective service in bags of various sizes and forms, and in which the parts can be readily separated and detached and assembled in "knocked down" form so that they occupy a flat compact space and the device can when out of use be conveniently carried within the bag.

In the drawings—Figure 1 is a perspective view of the tree device embodying my invention, parts being broken away to show the features of construction and its operative position being illustrated in dotted lines. Fig. 2 is a bottom plan view of the under side of the device. Fig. 3 is a detail cross-section, taken on the line $\alpha-\alpha$, Fig. 2. Fig. 4 is a detail cross-section taken on either of

the lines $y-y$, Fig. 2. Fig. 5 is a transverse vertical sectional view, taken through a traveling bag and showing the device in operative position therein as a tree device for expanding the bag in normal position. Fig. 6 is a view corresponding to Fig. 5 and showing the device in operative position for holding the bag open, its further operative position for retaining the contents of the bag being illustrated in dotted lines. Fig. 7 is a bottom plan view of the under side of the device, illustrating a modified construction of the base member. Fig. 8 is a detail vertical sectional view, taken on the line $z-z$, Fig. 7.

Corresponding parts in all the figures are denoted by the same reference characters.

Referring to the drawings, 1 designates the base of the device, which preferably comprises two strip members, 2 and 3, respectively, which are relatively slidable with relation to each other so that the base may be extended or contracted to readily adapt the device for operative service in traveling bags of different widths or sizes. In the preferred construction, the base members 2 and 3 are formed of metal plates, and to effect the relatively-slidable adjustable operation the main strip member 2 has its edges turned under, as at 4, to form a longitudinally-extending socket at the under side of the base 1 within which is slidably received the supplementary strip member 3. To the outer ends of the respective base strip members 2 and 3 are connected upwardly-extending resilient arms, 5 and 6, respectively, in strip form, which arms are preferably formed of strips or plates of spring metal. The connection of said resilient strips or arms with the respective strip members of the base is preferably detachable, and in the preferred construction for this purpose the outer end portions of the respective base strip members 2 and 3 have their edges turned under, as at 7 and 8, to form sockets at the under side which respectively and slidably receive the terminal bottom ends, 9 and 10, of the resilient arms 5 and 6, these ends being turned at right-angles to the upwardly-extending body portion of the arm.

The resilient arms 5 and 6 normally extend in perpendicular position at right-angles to the base 1, and one of the arms, 5, is provided at its terminal top end with a socket, 11, adapted to slidably receive the free end portion of the other arm, 6, this

socket being preferably formed by integral wings, 12—12, upon said arm 5, which wings are bent over above the surface of the arm to form the socket. Below the socket, said arm 5 slidably carries a collar, 14, within which is adapted to be received the terminal end, 15, of the other resilient arm 6, which extends beyond the socket, to retain the resilient arms in detachably connected operative position.

In operation, it will be understood that with the construction as above described the base 1 is adjustable to different degrees of extension or contraction and the resilient arms 5 and 6 are adjustable to various degrees of relatively bowed and detachably connected position. In practice, the device is placed within the bag, shown at 16, with the base 1 immediately above and transversely of the bottom, shown at 17, thereof, and with the resilient arms 5 and 6 extending upwardly and bearing against the inner sides of the respective sides of the bag body. Then, when it is desired to employ the device as a tree for sustaining the bag in normal shape when closed and out of use, the free end portion of the resilient arm 6 is inserted in the socket 11 of the resilient arm 5, to produce a spring bow of desired size, and the terminal end of the arm 6 is retained by the collar or slide 14, and thus when the bag is closed the spring bow formed by said arms will bear interiorly upon the respective sides of the bag and sustain the same in expanded position, as illustrated in Fig. 5. In like manner, the device may be employed as a means for retaining the contents of the bag in compressed position, by producing a bow constituted by the arms 5 and 6 and extending over and bearing upon the contents, as illustrated in Fig. 6. The device will also operate to retain the bag in open position during use, by disconnecting the resilient arm 6 from the resilient arm 5, in which position said upwardly-projecting arms will tensionally operate by pressure against the respective sides of the bag at the top, as illustrated in Fig. 6.

In Figs. 7 and 8, I have illustrated a modified construction in which the base 1, in lieu of being extensibly adjustable and constituted by relatively-slidable members, is constituted by a single strip, 18, which may be of wood and is adapted to the desired size, the detachable connection of the resilient arms 5 and 6 with said strip 18 being preferably effected by a construction embodying slots, 19, provided transversely and adjacent the respective ends of said strip. In this construction, the resilient arms 5 and 6 are respectively inserted through the slots 19 and brought to a relative position in which the terminal ends of their right-angular bottom portions extend outwardly and bear against the under side of the strip 18, for which

purpose the latter is preferably recessed, as at 20, to accommodate the body ends of the resilient arms within the plane of the bottom surface of said base strip.

It will be noted that, in the construction as herein shown, the resilient arms may be readily disconnected from each other and also detached from the base, and the device thus reduced to compact "knocked down" position in which the base and arms may be placed parallel to each other and will occupy a flat compact space, whereby the device is adapted to be conveniently carried in the bag.

Under some circumstances of preferred use, the tree device constituting my present invention may be employed in the bag with the base 1 extending transversely of the length of the bottom 17 of the bag, instead of transversely across the width of the bottom as shown in Figs. 5 and 6, and under such circumstances of lengthwise use in the bag the operation of the resilient arms 5 and 6 will be the same as when the device is employed crosswise of the bag, as will be readily understood.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. A tree device for traveling bags or the like, comprising a base adapted to rest within the bag and across the bottom thereof, resilient arms carried by said base and respectively extending upwardly from the end portions thereof and adapted to form a spring bow tensionally bearing against the inner sides of the upper portion of the bag, and means for detachably connecting the free end portions of said resilient arms to adjustably retain them under spring action in bowed form against their tensional spread upwardly and outwardly.

2. A tree device for traveling bags or the like, comprising a base adapted to rest within the bag and across the bottom thereof, and resilient arms carried by said base and respectively extending upwardly from the end portions thereof and adapted to form a spring bow tensionally bearing against the inner sides of the upper portion of the bag, the top end portion of one of said resilient arms carrying a socket slidably receiving

the free end portion of said other resilient arm.

3. A tree device for traveling bags or the like, comprising a base adapted to rest within the bag and across the bottom thereof, resilient arms carried by said base and respectively extending upwardly from the end portions thereof and adapted to form a spring bow tensionally bearing against the inner sides of the upper portion of the bag, the top end portion of one of said resilient arms carrying a socket slidably receiving the free end portion of said other resilient arm, and means carried by one of said resilient arms and slidably engaging the terminal end of said other resilient arm.
4. A tree device for traveling bags or the like, comprising a base adapted to rest within the bag and across the bottom thereof, said base being extensibly adjustable, and resilient arms carried by said base and respectively extending upwardly from the end portions thereof and adapted to form a spring bow tensionally bearing against the inner sides of the upper portion of the bag.
5. A tree device for traveling bags or the like, comprising a base adapted to rest within the bag and across the bottom thereof, resilient arms carried by said base and respectively extending upwardly from the end portions thereof and adapted to form a

spring bow tensionally bearing against the inner sides of the upper portion of the bag, said resilient arms being detachably connected with said base, and means carried by one of said resilient arms for engaging and retaining the free end portion of said other resilient arm.

6. A tree device for traveling bags or the like, comprising a base adapted to rest within the bag and across the bottom thereof, said base being constituted by relatively-slidable members whereby it is extensibly adjustable, resilient arms carried by said base and respectively extending upwardly from the end portions thereof and adapted to form a spring bow tensionally bearing against the inner sides of the upper portion of the bag, said resilient arms being detachably connected with said base, a socket upon one of said resilient arms slidably receiving the free end portion of said other resilient arm, and a device upon one of said resilient arms slidably engaging the terminal end of said other resilient arm.

In testimony whereof I have signed my name in the presence of the subscribing witnesses.

EVIE WALTON BRYSON.
